2 SHEETS—SHEET 2.

UNITED STATES PATENT OFFICE.

NORRIS O. MELLOTT, OF HARPER, CALIFORNIA.

FUMIGATING DEVICE.

1,287,389.

Specification of Letters Patent. Patented Dec. 10, 1918.

Application filed February 5, 1917. Serial No. 146,786.

To all whom it may concern:

Be it known that I, NORRIS O. MELLOTT, a citizen of the United States, and resident of Harper, in the county of Orange, and State 5 of California, have invented certain new and useful Improvements in Fumigating Devices, of which the following is a specification.

This invention relates to tree culture 10 appliances and has more especial reference to an improved fumigating device.

The dominant object of the invention is to provide means for efficiently fumigating trees, whereby, all parts of the same will be 15 disinfected, the tree being enveloped by the fumigating means to prevent the escape of the fumes of the disinfectant, and also, to prevent the waste of the same.

It is a more specific object of the invention 20 to provide a knock down or sectional fumigating device, whereby, the same may be set up about trees varying in size and shape in a minimum amount of time.

Another object of the invention is to provide 25 an adjustable cover or roof for the fumigating device so that the area or space within the same may be limited to accord with the height of the tree or trees to be fumigated, thus, preventing waste of the disinfectant.

Among other aims and objects of the invention may be recited the provision of a device of the character mentioned with a view to compactness, and in which the number 35 of parts are few, the construction simple, the cost of production small, and efficiency and operation high.

The invention consists, furthermore, in the novel arrangements and the combinations of 40 parts of the device, as well as in the details of construction of the same, all of which will be more fully described in the following specification and then finally embodied in the clauses of the claim which is appended to the 45 specification and which forms an essential part of the same.

The invention is clearly illustrated in the accompanying drawings, in which:

Figure 1 is a perspective of my improved 50 sectional fumigating device;

Fig. 2 is a fragmentary side elevation of the same with one of the walls thereof removed;

Fig. 3 is a horizontal section through the fumigator showing the arrangement of the 55 roof thereon, when in adjusted position;

Fig. 4 is a detail in perspective of the wall fastening means;

Fig. 5 is a fragmentary detail in perspective of a portion of the roof; and 60

Fig. 6 is a top plan of a slightly modified form of fumigator.

Similar characters of reference are employed in all of the above described views 65 to indicate corresponding parts.

Referring now more specifically to the several figures of the said drawings, there is provided a plurality of wall sections, generally indicated by the numeral 5, which wall sections comprise substantially rectangular shaped frames 6 having arranged transversely thereof at spaced apart intervals cross bars or braces 7, it being noted, that the space between certain of the cross bars 7 varies. Over one face of the walls 5 there 70 is arranged a suitable covering 8, the said covering being secured in position upon its respective wall frames 6 by embedding the top, bottom and side edges within suitable grooves formed within the adjacent portion 80 of the said frames. To retain the edges of the covering 8 in proper position with respect to the rectangular frame 6, a suitable cement may be employed or by arranging beading adjacent the jointure of the said 85 covering with the grooves in the various portions of the frame 6 or by passing fastening devices through the same the covering may be also properly secured. In order that the various walls 5 may be maintained in proper 90 assembled relation when the fumigating device is set up about a tree the opposite side portions 6 of the said walls are provided with rounded tongues and grooves 9 and 10, respectively, the tongue of one wall being 95 adapted to interlock with the adjacent groove upon the next wall. Those edges of the said side portions adjacent the tongues 9 are beveled as at 9' the purpose of which will be subsequently apparent. By so connecting the walls, it will be appreciated, that 100 undue lateral movement of the same when arranged in set up position about a tree or the device be to fumigated will be prevented.

Other grooves are arranged longitudinally 105 upon the inner faces of the various cross

bars 7 and provide means for receiving an adjustable cover or roof therebetween, the construction of which will be more fully hereinafter described.

- 5 Arms 11 having bifurcated end portions 12 and a plurality of apertures 13 formed therein are secured to certain of the ends of the cross bars 7 and project beyond their respective walls 5, whereby, eye bolts as arranged in proximity to the same upon the adjacent section or specifically, upon the adjacent cross bars may be received between the said bifurcated portions 12 thereof, the eye bolts being indicated by the numeral 14
- 10 and secured in position upon the cross bars 7 by means of eye screws 15 which are engaged with the looped extremities of the same. To lock the eye bolts 14 within the bifurcated portions 12 of the said arms 11,
- 15 20 wing nuts 16 are turned into engagement with the screw threaded extremity thereof. It of course, is to be understood that suitable fastening devices are passed through the apertures 13 formed within the arms 11,
- 25 25 whereby the same may be rigidly secured to the various arms of the walls 5.

An opening 17 is formed within the lower portion 1 of the wall 5 and has arranged adjacent the sides of the same a pair of vertically disposed grooved guide strips 18, the opposite ends of which are secured to the adjacent cross bars 7. A door 19 is slidably mounted between said grooved guide strips 18 and is provided upon the opposite side 30 portions thereof, with suitable tongues adapted for reception in the said grooves. By providing the opening within the wall 5, it is evident, that the placing of the disinfecting means within the fumigating device is 35 facilitated, and that when the said disinfectant means are properly placed, the door 19 may be readily moved to its closed position. Thus, the escape or waste of the fumes of the disinfectant will be prevented.

- 40 45 A cover comprising an approximately square frame 20 having a covering 21 arranged thereover is adapted to be received by the upper portion of the fumigating device, and is of a size to permit the sliding 50 of the same to various positions therein. The outer marginal edges of the frame 20 are of a width to permit the same to be readily received between the alined grooves or ways formed within the inner faces of 55 the cross arm 7, thus, the roof may be adjusted to various positions within the fumigating device, depending upon the height of the tree to be fumigated. Furthermore, by varying the spacing between the cross 60 arms 7 the roof may be accurately adjusted to the height of the tree, whereby to cause the same to be thoroughly fumigated and to prevent the waste of the disinfectant. Hooks 22 are pivotally engaged with the side 65 portions of the roofing frame 20, by means

of suitable eye screws and are adapted to engage eyelets 23 arranged upon the upper marginal edges of the cross bars 7 of the various wall frames 6 and as a consequence, the said roof may be securely maintained in 70 position upon the top or upper extremities of the walls 5.

With a view toward providing fumigating devices which may be snugly arranged about trees varying in size and shape, it is 75 to be understood that I may change the shape of the roof or cover to conform thereto. To this end, I have shown in Fig. 6 a triangularly shaped disinfecting device, indicating the same in its entirety by the 80 numeral 24. The triangular fumigating device is constructed in exact accordance as the device hereinbefore described, the beveled edges 9' permitting the rounded tongues to properly adjust themselves in 85 their respective grooves to form the triangular shape. A roof 25 is provided and is of a shape to correspond to the shape of the housing 24, the roof being capable of vertical adjustment within the said housing 90 whereby the same may be adapted to trees of varying heights.

From the foregoing, it will be appreciated by workers in the art that I have provided an exceedingly simple fumigating device 95 and one which will be readily assembled and disassembled in a minimum period of time. Furthermore, by varying the shape of the fumigating device, the same may be applied to trees of practically any shape and 100 will by snugly enveloping the tree, cause the fumes from the disinfectant to be thoroughly circulated about and through the same.

I desire to have it understood, that the improved fumigating device may be constructed of any size, such as conditions or preference may dictate, and further, that instead of forming the side walls of frame, over which frame suitable coverings are arranged, I may construct the same of single 110 pieces of material, such as wood, metal or the like.

As indicated, I do not wish to be understood as confining the invention to the particular embodiments chosen for illustration 115 herein, nor to the exact construction and arrangement and adaptation of the parts shown and described, but I reserve the right to make any changes and alterations that fairly fall within the spirit and scope of the 120 invention.

I claim:

In a device of the character described, a sectional skeleton structure including vertical and horizontal pieces, said horizontal 125 pieces being arranged in alined sets and having grooves formed in their inner faces, brackets carried adjacent certain of the marginal portions of the skeleton structure sections, bolts pivoted to the remaining mar- 130

ginal portions of said sections engageable with said brackets for detachably connecting the sections, panels for the skeleton structure sections, one of said panels having 5 a way therein, a closure slidably arranged adjacent the way in said panel, and a top having a marginally disposed tongue ar-

ranged thereabout receivable in the grooves formed in said alined sets of horizontal pieces.

10

In testimony whereof, I affix my signature hereto.

NORRIS O. MELLOTT.
